PRODUCTION OF COLORED PICTURES

Ernst Bauer, Dessau, Germany, assignor, by
means assignments, to Agfa Ansco Corporation,
Binghamton, N. Y., a corporation of Delaware

No Drawing. Application August 5, 1936, Serial
No. 94,344. In Germany August 17, 1935

1 2 Claims. (CL 95-2)

My present invention relates to the production of colored pictures.

One of its objects is to provide a process for the production of improved colored pictures. Further objects will be seen from the detailed specification following hereafter.

Colored pictures have been made by developing in colors a silver halide emulsion by means of a developer, the oxidation product of which couples with a dyestuff component. It has also been proposed to convert the developed silver picture in a layer into a colored picture by the reaction of an azo-dyestuff component on silver anti-diazotate. By the first-mentioned process one obtains, indeed, blue and red tinted pictures free from objection; the yellow picture, however, is, generally, somewhat too weak. By the anti-diazotate method there is obtained a beautiful red and yellow tint but the blue tint is less good.

20 The present invention is based on the observation that the constituent color pictures can be harmonized to a great extent, if there is formed on a photographic material, having several layers superimposed on each other on one or both sides of a support, one or more partial color pictures by color development with diethyl-para-phenylene-diamine or the like, and other partial color pictures by the silver diazotate process through coupling with an azo dyestuff component. In particular, it is advantageous to produce the blue and red constituents by color development and the yellow by the silver anti-diazotate method.

For the color development there come into question particularly color-forming components which have substantive properties in respect of the binding agent, like those which are applied in the process of the co-pending application Ser. No. 72,718 filed by Wilmanns, Schneider and the inventor of the present application.

40 The azo-dyestuff pictures may be obtained, in particular, by the process of U. S. Patent 1,963,197 with use of dyestuff components which yield equal color tints by both methods.

The following example illustrates the invention:

The film to be used in this invention may be built up as follows:

The first, not specially sensitized layer, contains the substantive compound p-salicylic acid benzidine. The second orthochromatic layer contains, for example, 1-(diphenyl)-3-methyl-5-pyrazolone. The third layer contains as dyestuff component 1,2-hydroxy-naphthoic acid benzidine. By color development with the aid of p-dimethylamino-aniline there is produced in the second

layer a red picture and in the third layer a blue picture.

If the latent image is developed with p-dimethylamino-aniline there is produced, besides 1 mol. dyestuff 4 mols. silver. After removing the undeveloped silver bromide the silver picture is converted in the known manner into a silver salt and this is converted into silver anti-diazotate by means of a soluble anti-diazotate, for instance diphenyl-danti-diazotate. In the bath containing a weak acid solution the liberated diazonium compound couples with the p-salicylic acid benzidine. The silver salt remnant in the several layers is removed by fixing so that pure dyestuff pictures are present in the finished film.

The film may also be developed with aid of an ordinary black and white developer and fixed. This operation produces a better threshold value than the developer p-dimethylamino-aniline and better freedom from fog. The silver picture is then converted into a silver salt and this salt further developed with p-dimethylamino-aniline. There is thus produced a silver picture and a dyestuff picture. The silver is again converted into a salt and, as described above, caused to react with anti-diazotate. If desired the order of the treatments may be reversed.

Further, the silver produced in the black-and-white development may be dissolved and after a second exposure the residual silver bromide may be developed with p-dimethyl-amino-aniline and the metallic silver thus produced converted in known manner by means of silver anti-diazotate into an azo-dyestuff picture.

One can, therefore, by this invention obtain as desired positive or negative color pictures which by combination of the individual development processes may be profoundly influenced in their tints. A further possibility of the correction of color tint resides in the fact that one or other of the processes need not be allowed to proceed through the complete depth of the three layers but may be only partial in its action.

What I claim is:

1. A process of producing colored pictures with the use of a photographic material having three superimposed emulsion layers and containing in the first emulsion layer p-salicylic acid benzidine, in the second layer 1-diphenyl-methyl-5-pyrazolone, and in the third layer 1,2-hydroxynaphthoic acid benzidine, which comprises color-developing said photographic material, removing the undeveloped silver salt, converting the silver picture still present after color-development into silver anti-diazotate, liberating the diazonium

compound to couple with said p-salicylic acid benzidine, and fixing said photographic material.

2. A process of producing a colored photographic picture, which comprises exposing to light controlled by an object to be reproduced a three-layer photographic element, two layers of said element comprising a color forming development component fast to diffusion for the blue and the red picture respectively, and one layer comprising a substantive azo dye component; devel-

oping said element with an aromatic amino developer thereby forming a silver and color picture in said two first-named layers in a single development step, and a silver picture in said second-named layer, removing the undeveloped silver salt, converting the residual silver picture into a silver antidiacetate picture and causing said substantive azo-dye component to couple with said silver-antidiacetate.

ERNST BAUER. 20
